(57) CLAIM

The ornamental design for footwear, as shown and described.

DESCRIPTION

5. Footwear

Fig. 5.1 is a perspective view of footwear;

Fig. 5.2 is a side view of the footwear;

Fig. 5.3 is a top view of the footwear; and

Fig. 5.4 is a rear view of the footwear.

The writings visible, either partially or completely, on the shown footwear do not form part of the design for which protection is sought.

1 Claim, 4 Drawing Sheets
